PORTABLE DANCE FLOOR OR MAT

Filed June 18, 1934

INVENTOR,
HERBERT B. MUELLER.
BY *Martin P. Quinn* ATTY.

UNITED STATES PATENT OFFICE

2,019,692

PORTABLE DANCE FLOOR OR MAT

Herbert B. Mueller, Los Angeles, Calif.

Application June 18, 1934, Serial No. 731,109

4 Claims. (Cl. 20—6)

My invention relates to a portable dance floor or mat and has for its principal objects, the provision of a relatively simple, practical and inexpensive dance floor or mat that is composed of 5 a plurality of sections connected by hinges so that said sections may be folded flat against each other in order to occupy as little space as possible when the floor or mat is packed for storage or transportation and to provide simple and efficient 10 means whereby any number of the hinge connected mat sections may be assembled and secured to each other to form a dance floor of any desired size.

Further objects of my invention are, to provide 15 a dance floor or mat that may be conveniently folded and transported from one point to another, which floor or mat when unfolded for use presents a smooth, finished surface, further, to provide a folding portable dance floor or mat 20 that has two finished surfaces, thereby enabling the floor or mat to be reversed for use and consequently doubling its life or period of usefulness.

Further objects of my invention are, to provide 25 an improved form of hinge for connecting the folding sections of the floor or mat and to provide simple and efficient means for detachably connecting the edges of the floor or mat to each other when an enlarged dance floor or mat is provided.

With the foregoing and other objects in view 30 my invention consists in certain novel features of construction and arrangements of parts that will be hereinafter more fully described and claimed and illustrated in the accompanying drawing in which:

Fig. 1 is a plan view of a dance floor or mat 35 constructed in accordance with my invention and composed of three sections, also showing the end portion of an adjacent floor or mat.

Fig. 2 is an enlarged section taken approximately on the line 2—2 of Fig. 1 and showing one 40 of the floor or mat sections swung into position beneath the intermediate section.

Fig. 3 is an enlarged detail view showing the 45 joint between two of the floor or mat sections.

Fig. 4 is an enlarged elevational view taken looking in the direction indicated by the arrow 4 45 in Fig. 2.

Fig. 5 is a section taken on the line 5—5 of 50 Fig. 4.

Fig. 6 is a horizontal section in detail and showing the hook that is utilized for securing the edges of two of the floor or mat members to each other.

Fig. 7 is a vertical section taken on the line 55 7—7 of Fig. 6.

Fig. 8 is a perspective view of a member that forms a part of the securing means illustrated in Figs. 6 and 7.

In the accompanying drawing I have shown

my improved dance floor or mat composed of three sections or panels which are designated A, B and C, said panels being identical in size and practically similar in construction.

The panels may be of any desired size, although 5 as illustrated I prefer to form the panels so that the length of each panel equals the width of two panels, for such measurements facilitate the assembly of a number of the floors or mats when 10 an enlarged dance floor is produced.

Each section or panel is composed of a plurality of strips 10 of relatively thin material such as hard wood laid edge to edge.

Formed in two adjacent edges of each section or panel, are grooves 11, preferably V-shape and 15 formed on the other two edges of the panel, are corresponding V-shaped ribs 12 that are adapted to enter the grooves 11 when a number of the floor or mat sections are assembled.

The inner edges of the panels A and C are connected to the adjacent edges of intermediate panel B by hinges that are identical in construction, but when the hinges are applied to the panels, one pair, for instance, the pair that connect the panels B and C are reversed or turned 25 upside down with respect to the hinges that connect panels A and B and which arrangement is necessary in order to permit panel A to be folded over onto the top of panel B and for panel C to be folded into position beneath intermediate 30 panel B.

Thus the three panels forming the floor or mat section may be folded so as to occupy comparatively little space when the section is packed for 35 storage or transportation.

Each hinge comprises a pair of channel-shaped members 13 that are mortised into the adjacent edges of the panels A, B and C and connecting each pair of hinge members 13 is a pair of hinge 40 links 14.

The hinges when applied to the panels are arranged so that their outer surfaces are flush with the surfaces of said panels.

In order to firmly hold the strips 10 in assembled relation, rods 15, preferably of wire, extend 45 transversely through the strips adjacent to the ends of the panels, both ends of said rods being threaded for the reception of nuts 16 and the latter being provided in their edges with diametrically opposite notches 17 for the reception 50 of a spanner wrench that is used for the manipulation of said nuts.

The outer edges of the panels A and C are notched or recessed as designated by 18 for the 55 reception of the nuts 16 and the central portions of the adjacent edges of the hinge members 13 between the links 14, are notched as designated by 19 for the reception of the corresponding nuts.

Formed in the central portion of the end of each panel A, B and C at the end from which the 60

ribs 12 project, are recesses 20 for the accommodation of the hooks that serve to unite the floor or mat sections when a number of the same are assembled to form a large dance floor and a 5 pair of such recesses 20 are formed in the edge of panel A, along which the rib 12 is formed.

Each hook constructed as illustrated in Fig. 6 comprises a body plate 21, on one end of which is formed a hook 22 and formed in plate 21, is 10 a substantially T-shaped opening 23.

Occupying the longitudinal leg of the opening 23, is a square block 24 and formed integral with the ends thereof, are trunnions 25 that are mounted for rotation in bushings 26, the latter being seated in the walls of the panels above and 15 below the recess 20.

Formed through the trunnions 25 and block 24, is a non-circular opening 27 for the reception of the key that is utilized in turning the 20 hooks from one position to another.

Positioned in the transverse portion of the opening 23 in each hook and bearing against one of the faces of the corresponding block 24, is a bow spring 28.

25 Formed in the ends of the panels opposite from the ends in which the recesses 20 are formed and in direct longitudinal alignment therewith, and also in the edge of panel C, and in alignment with the recesses that are formed in the edge of panel 30 A for the accommodation of the hooks, are recesses 30 for the accommodation of the hooks 22 when the same are swung outwardly from their pockets 20.

Seated in the panels and passing through these 35 recesses, are pockets 30^a and pins 31, which are engaged by the hooks when a number of the floor or mat sections are assembled.

Each hook 22 is provided with a notch 32 for the reception of the pin 31 and the outer one of 40 the edges 33 of the opening in the hook which leads to the notch 32 is formed eccentric to the axis of the block 24 and trunnions 25 so that when the hook is swung outward to engage the corresponding pin 31, said hook will be moved slightly 45 lengthwise against the resistance offered by bow spring 28 so as to exert pulling strains on said hook when the engaged pin 31 is seated in the notch 32.

As a result of this arrangement the floor or mat 50 sections are firmly held in assembled relation when a large dance floor or mat is formed.

While the hooks are not in use they are swung into the pockets 21, as shown by dotted lines in Fig. 6 and to swing said hooks outward a key is 55 inserted in the opening 29 in the block and trunnion member 24, 25 and the latter partially rotated so as to impart corresponding movement to the hook.

The length of each panel A, B and C is exactly 60 twice its width and as the hooks and pins at the ends of said panels are located midway between the side edges of said panels and the pins in the outer edge of panel C and the hooks carried by the outer edge of panel A are spaced from the 65 corners of said panels the proper distances, it is a very easy matter to assemble a number of the floor or mat sections to form a relatively large dance floor.

The hinged panels forming each section of a 70 dance floor or mat may be readily folded together into a comparatively small compass so that the sections are readily portable and may be conveniently transported from one place to another and the sections are reversible so as to provide two 75 smooth dancing surfaces.

Any number of sections may be assembled to form a relatively large dance floor and the fastening means between sections may be conveniently manipulated to securely hold the sections in assembled relation.

Thus it will be seen that I have provided a portable dance floor or mat that is relatively simple in construction, inexpensive of manufacture and very effective in performing the functions for which it is intended.

It will be understood that minor changes in the size, form and construction of the various parts of my improved portable dance floor or mat may be made and substituted for those herein shown and described without departing from the spirit 15 of the invention, the scope of which is set forth in the appended claims.

I claim as my invention:

1. In a portable dance floor or mat, a unit 20 composed of three panels of equal size, channel-shaped members positioned on the inner edges of the end panels and on the side edges of the intermediate panel and hinge links connecting the respective pairs of channel-shaped members and arranged so that one of the end panels may 25 be swung into position beneath the intermediate panel and the other end panel swung into position above the intermediate panel.

2. In a portable dance floor or mat, a unit 30 composed of three panels, hinges connecting the inner side edges of the end panels with the side edges of the intermediate panel, the outer side edges of one panel and the corresponding edges of all of the panels at one end being provided with recesses, blocks mounted for rotation in said 35 recesses, a hook carried by each block and mounted to rotate therewith and slide thereon and a spring for yieldingly resisting the sliding movement of the hook in one direction.

3. In a portable dance floor or mat, a unit 40 composed of three panels, hinges connecting the inner side edges of the end panels with the side edges of the intermediate panel, the outer side edges of one panel and the corresponding edges of all of the panels at one end being provided with 45 recesses, blocks mounted for rotation in said recesses, a hook carried by each block and mounted to rotate therewith and slide thereon, a spring for yieldingly resisting the sliding movement of the hook in one direction, all of which hooks 50 project beyond the edges of the panels, the outer side edge of the panel opposite the panel in the side edge of which certain of the hooks are seated and the ends of all of the panels opposite the ends in which hooks are seated being recessed 55 for the reception of the projecting ends of hooks on the panels of adjacent units and pins passing through said last mentioned recesses for the reception of the hooks that are inserted therein.

4. In a portable dance floor mat, a unit 60 composed of three panels, hinges connecting the inner side edges of the end panels with the side edges of the intermediate panel, hooks mounted for partial rotary and for sliding movement in the outer edge of one of said panels and in the corresponding end edges of all of the panels, the opposite end edges of all of the panels and the side edge of the panel opposite from the panel in the side edge of which the hooks are seated, being recessed and pins passing through said recesses 70 for the reception of hooks that project from the edges of adjacent units.
